UNITED STATES PATENT OFFICE.

WILLIAM P. GRAHAM, OF NEW YORK, N. Y.

DESIGN FOR A PLATE OR SIMILAR ARTICLE.

Application filed October 8, 1924. Serial No. 10,991. Term of patent 7 years.

To all whom it may concern:

Be it known that I, WILLIAM P. GRAHAM, a citizen of the United States, and a resident of New York, in the county of New York and State of New York, have invented a new, original, and ornamental Design for Plates or Similar Articles, of which the following is a specification, reference being had to the accompanying drawing, forming part thereof.

In the accompanying drawing:

The figure is a top view of plate showing my new design, the ornamentation shown at the top of the plate being continuous throughout the circumference of the plate.

I claim:

An ornamental design for a plate or similar article as shown.

WILLIAM P. GRAHAM.
